UNITED STATES PATENT OFFICE

98,044

DESIGN FOR A COIN SAVINGS BANK OR SIMILAR ARTICLE

David H. Zell, Brooklyn, N. Y.

Application September 17, 1935, Serial No. 58,596

Term of patent 3½ years

To all whom it may concern:

Be it known that I, David H. Zell, a citizen of the United States and a resident of Brooklyn, in the county of Kings, State of New York, whose post office address is 734 E. 7th Street, Brooklyn, New York, have invented a new, original, and ornamental Design for a Coin Savings Bank or Similar Article, of which the following is a specification, reference being had to the accompanying drawing, forming part thereof.

I claim:

The ornamental design for a coin savings bank or similar article as shown.

DAVID H. ZELL.
